UNITED STATES PATENT OFFICE.

WILLIAM S. ROWLEY, OF PALMYRA, NEW JERSEY, ASSIGNOR TO H. W. BUTTERWORTH & SONS CO., OF PHILADELPHIA, PENNSYLVANIA, A CORPORATION OF PENNSYLVANIA.

CLOTH-CLAMP FOR TEXTILE MACHINERY.

1,333,134.

Specification of Letters Patent.

Patented Mar. 9, 1920.

Application filed July 27, 1918. Serial No. 246,961.

To all whom it may concern:

Be it known that I, WILLIAM S. ROWLEY, a citizen of the United States, and resident of Palmyra, county of Burlington, and State 5 of New Jersey, have invented an Improvement in Cloth-Clamps for Textile Machinery, of which the following is a specification.

My invention has for its object the construction of a cloth clamp for tenting and other textile machinery, which will insure a more positive grip upon the selvage edges of the fabric than has heretofore been possible with automatic clamps of the general 15 nature to which my present invention relates.

In clamps having a pivoted jaw adapted, when released by the operating cams, to grip the fabric upon a plate or surface 20 fixedly attached to the chain link, there has been much difficulty to insure proper clamping operation because the thicknesses of the fabric and surface texture varies and thereby changes the gripping inclination of the 25 clamping jaw; and moreover, this angle must be such that for the lightest fabrics the gripping edge of the jaw will not be liable to spring over the fixed plate and thus release the cloth, which provision causes the jaw 30 to have so great an inclination when heavy fabrics are being treated, that they are not securely held and defective treatment results. If the gripping edge of the jaw is made sharper than usual to insure better 35 biting upon the fabric, then liability to cutting the more delicate fabrics results. In the usual practice, the plates of the clamps on opposite sides of the machine are in the same horizontal plane and the gripping 40 jaws extend obliquely thereto in opposite directions and at pronounced inclinations of approximately 20 to 30 degrees; and such inclinations, not only make it difficult to hold all classes of fabrics, but the failure to 45 properly hold them produces defective treatment and unmarketable goods. These defects are entirely overcome by my improvements hereinafter described.

My invention consists in having the gripping surface of the cloth clamp arranged at an upward incline to the normal level between the clamps at the opposite sides of the machine and shortening the length of the pivoted jaw so that it may swing almost 55 to a vertical position, whereby it produces

a powerful gripping action upon the cloth and without any danger of being drawn through the clamp. In other words, instead of the plate being tangential to a vertical line through the pivot of the jaw, it is made 60 at a slight incline thereto so as to bisect the arc made by the gripping edge of the approximately vertical jaw in swinging adjacent to its gripping position. Furthermore, in a clamp of this modified character, 65 the gripping power being so greatly increased, it is possible to materially reduce the sharpness of the gripping edge and thereby reduce the danger of injury to the fabric. 70

With the above and other objects in view, the nature of which will be more fully understood from the description hereinafter, the invention consists in the novel construction of cloth clamp for textile machinery as 75 hereinafter more fully described and defined in the claim.

Referring to the drawings: Figure 1 is a cross section illustrating the relation of my improved cloth clamps when used in a 80 tenting machine; Fig. 2 is a front elevation of my improved cloth clamp; Fig. 3 is a transverse section of the same; and Fig. 4 is a sectional view of a modified form of clamping plate. 85

Referring to Fig. 1, 2, 2, are the side frames of a tenting machine and have suitable guideways for the chains of cloth clamps 3, 3, which, while being fed through the machine, are caused to have a relative 90 reciprocation by reason of opposite reciprocations given to the two side frames 2, 2, all of which is understood by those skilled in the art. 4 indicates the cloth which is stretched between the two sets of clamps 95 3, 3, and in practice may be considered as occupying a horizontal plane. In this figure it will be observed that the dotted lines 9, 9, extend from the surfaces of the two opposite clamps 3, 3, and intersect above the horizontal plane between the clamps, and this is 100 a particular feature of my invention.

Referring more particularly to the details of the cloth clamps themselves as shown in Figs. 2 and 3, 5 is the link portion 105 by which the clamps are jointedly connected, 6 is the clamp bed cast integral therewith and provided with the overhanging arms 13, all of which may be considered generally as of usual construction. In practice it has 110

been customary to provide a flat plate upon the bed 6, the clamping surface of which has been made horizontal; but in my improved construction, this plate 8 is secured upon the bed 6 so as to present an inclined clamping surface. This inclination is indicated by the dotted line 9 as compared with the horizontal plane indicated by dotted line 10, Fig. 3; and to insure a rigid construction the bed 6 may have its upper surface inclined to receive the plate 8. The plate may have a downward front flange 7 and be secured in position by rivets or in any other suitable manner. It is manifest that the use of a separate plate 8 is not essential, but is advantageous as providing a brass surface upon which to clamp the fabric instead of a cast iron surface of the bed 6 itself.

14 is the gripping jaw and is pivoted upon the pin 15 extending through the free ends of the arms 13 and parallel to the longitudinal surface of the plate 8. This jaw has an upper arm 14^a for contacting with the usual cams (not shown) for automatically opening and closing of the clamps as they pass about the respective ends of the longitudinal frames of the machine. The clamp jaw 14, at its rear, is provided with an arm 16 upon which is pivoted the trip finger 17 whose forward part moves freely through a slot 11 in the plate 8 and bed 6 and whose rear part 18 rests upon the plate 8 at the rear of the slot for controlling the position of gripping upon the cloth, all as heretofore employed.

Referring to Fig. 3, it will be observed, that by reason of the inclining of the surface of the plate 8, the movable jaw 14 is enabled to assume almost a vertical position in its most effective gripping action, and this too without danger of being pulled forward and off the plate 8, as would be the case if said plate were not inclined to bisect the arc described by the gripping edge of the jaw. It will further be seen that because of this almost right angles of the jaw to the plate, the gripping edge of the jaw may be greatly more blunt than has heretofore been necessary and hence removes danger to cutting of the fabric.

In Fig. 4, I have shown a modified form of the plate 8, the same having the upward incline at its forward portion only instead of over its whole surface. The part 7^a may be horizontal and the part 8 inclined to correspond to the inclined dotted

line 9, and it will be understood that this will suffice as it is only necessary to have the incline on that portion which coöperates with the clamping jaw 14 with the various thicknesses of fabrics requiring treatment.

Prior to the use of my improved clamp very great difficulty was experienced in treating fabrics of various thicknesses upon a tentering machine as ordinarily constructed and much loss resulted by reason of the defective results obtained. Commercial experience with my improved clamp herein described has demonstrated the fact that with their use, all such defects heretofore existing are entirely and effectively overcome.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:

In a cloth clamp, a cast metal body having rigid integral overhanging arms and a clamping surface rigidly positioned below the arms and forming one of the jaws of the clamp, combined with a pivoted clamp-jaw hinged to the overhanging arms and normally in a substantially vertical position when in the act of clamping the cloth upon the rigid surface constituting a part of the other jaw, said pivoted jaw having a relatively sharp clamping edge, the clamping surface of the body immediately upon each side of a vertical plane through the axial hinge of the pivoted jaw formed in a continuous incline upward toward the open side of the clamp to provide coaction with the hinged jaw when in a substantially vertical position, whereby the pivoted jaw is adapted to clamp fabrics of various thicknesses with positiveness and with a maximum clamping action.

In testimony of which invention, I hereunto set my hand.

WILLIAM S. ROWLEY.
